HERMAN C. HEERMANCE, OF CLAVERACK, NEW YORK.

Letters Patent No. 61,831, dated February 5, 1867.

IMPROVEMENT IN MATTING FOR CARPET LINING, &c.

The Schedule referred to in these Letters Patent and making part of the same.

TO ALL WHOM IT MAY CONCERN:

Be it known that I, HERMAN C. HEERMANCE, of Claverack, in the county of Columbia, and State of New York, have invented certain new and useful Improvements in Matting; and I do hereby declare that the following is a full, clear, and exact description of the same, reference being had to the accompanying drawings, making a part of this specification, in which—

Figure 1 is a plan view showing the principal feature of my invention.

Figure 2 is an edge view of the same.

Figure 3 is an edge view showing both features of my invention.

Similar letters of reference indicate corresponding parts in all the figures.

This invention consists in the construction of matting, to be placed under carpets or used for other purposes, of straw, grasses, rushes, or other similar vegetable growths, sewed or stitched together in such manner that while the straw or equivalent material constitutes the body or *weft* of the fabric, the sewing serves the purpose of a *warp* to hold the *weft* together, whereby a flexible fabric of any desired thickness is obtained, which may be placed underneath carpets to enable dirt and dust to sift through the same and prevent the excessive wear thereof when placed in contact with a hard floor, with much greater ease and convenience than the layer of straw ordinarily employed for that purpose, and whereby a much more uniform and elastic thickness of straw or equivalent material underneath the carpet is secured than by such ordinary layer, and whereby such thickness of straw or other material, or, in other words, of matting, may be taken up and shaken to remove dirt therefrom with as great facility as the carpet itself, the said matting being, furthermore, not only capable of being used underneath carpets as aforesaid, but also for other purposes for which matting is commonly employed. The invention further, consists in the combination, with matting constructed as described, of paper secured either to one or both sides of the same by the same sewing that constitutes the *warp* thereof, whereby the matting is made stronger and less liable to injury from being handled.

As represented in the drawings, the matting is made of the straw of wheat, rye, oats, or other similar grain. The straw is first laid or formed into a layer of the same thickness as that desired for the finished matting, with the straws or stems *a*, composing the same, placed in a position nearly or quite parallel with each other, and transversely to the length of the finished strip of matting. Being thus arranged in a layer of the desired thickness, the said layer is sewed longitudinally either by hand or by any suitable mechanism, in such manner that any desired number of seams or rows of stitching, *b*, are formed transversely to the length of the straw, so that the thread or twine employed in making the said seams, being passed repeatedly through the straw, binds the straws or stems thereof securely together, so as to form a fabric of a thickness equal to that of the layer of straw, with the said straw constituting the *weft* of the fabric which is held together by the seams or rows of stitching *b*, which act as the *warp* thereof. One of these rows of stitching is placed close to each of the lateral edges of the sheet or strip of matting and parallel with the same, so as to confine the ends of the straw, while the remaining rows of the said stitching are situated at equal or at any suitable or desired distances apart between the two outermost rows just mentioned, and are also formed longitudinally in the said strip of matting so as to bind or confine together the central or middle portion of the straw constituting the *weft* of the fabric as just herein described. When desired, instead of having the rows of stitching *b* extending longitudinally with the strip of matting as just set forth, they may be made diagonal thereto, and consequently also diagonal to the length of the straws or stems of the straw which constitutes the *weft* of the fabric, in which case the said rows of stitching will act to hold the straw together, or, in other words, as the *warp* of the fabric, in substantially the same manner as when formed parallel with the lateral edges of the sheet or strips, as just hereinbefore explained.

It is designed that the operation of sewing or forming the rows of stitching be performed by a sewing machine of any suitable construction, and it is preferred to feed the layer of straw (or equivalent material of which the *weft* of the matting is formed) to such sewing machine between two endless belts or aprons operated by any suitable mechanism. Instead of making the *weft* of the fabric of straw, as represented in the drawings, and as just hereinbefore fully set forth, the said *weft* may be made of grasses, or of rushes, or of any similar vegetable growths, which are arranged in the same manner as the straw to form the *weft* of the fabric, and are in like manner stitched or sewed together by rows of stitching, which act as the *warp* thereof. When it is desired

to give the matting a greater degree of strength in order to enable it to better resist the effects of handling or transportation, or for any other reason, a layer composed of one or more thicknesses of paper is secured either upon one side thereof, as shown at *c*, in fig. 3, or upon both sides of the same, as at *d d*, in the said figure; the paper being secured to the matting by the seams or rows of stitching *b*, the stitches of which pass through the said paper as well as through the weft of the fabric, and thus attach it securely to the said weft. This matting is much better adapted for being placed underneath carpets to lessen the destructive wear thereof than the layer of straw commonly employed for that purpose, inasmuch as it may be laid down under the carpet with much greater ease and convenience, and is also of a more uniform thickness than such layer, and being somewhat more compact than such layer is proportionally more elastic, and consequently furnishes a more efficient support to the carpet, while the proper sifting of the dirt or dust from the carpet into or through the matting is not interfered with in the least; while the said matting may be taken up and shaken to remove the dirt therefrom with as great facility as the carpet itself. Furthermore, the matting being very flexible, and capable of being made of any desired thickness, may be employed for any of the purposes for which matting is ordinarily used; and as it may furthermore be made at a very moderate cost, both as regards the intrinsic value of the material and the expense of manufacture, it furnishes a very cheap and efficient substitute for the matting in common use.

What I claim as new, and desire to secure by Letters Patent, is—

1. A matting composed of straw, grasses, rushes, or other similar vegetable growths, sewed together in the manner substantially as and for the purposes set forth.
2. The combination, with a matting constructed as herein described, of sheets of paper or other thin fabric, secured upon one or both sides thereof by means of the sewing that constitutes the warp thereof, substantially as herein set forth for the purpose specified.

HERMAN C. HEERMANCE.
